UNITED STATES PATENT OFFICE.

PAUL J. KOHLER, OF CARRICK, PENNSYLVANIA.

TUBE-CUTTING MACHINE AND CRIMPER.

1,415,099.

Specification of Letters Patent. Patented May 9, 1922.

Application filed March 27, 1919. Serial No. 235,538.

To all whom it may concern:

Be it known that I, PAUL J. KOHLER, a citizen of the United States of America, residing at Carrick, in the county of Allegheny and State of Pennsylvania, have invented certain new and useful Improvements in Tube-Cutting Machines and Crimpers, of which the following is a specification, reference being had therein to the accompanying drawings.

The invention relates to machines for cutting tubes and refers more particularly to machines for cutting stove-pipes, ducts, etc., made of tin or sheet iron. One object of the invention is to provide a portable construction which can be readily clamped to a work-bench and which will cut the tube intermediate its ends without damaging either end portion. Another object is to provide a construction in which there are cooperating cutters adjustable toward each other and in which there is means for rotating these cutters. A further object is the provision of an adjustable stop for limiting the length of tube to be cut. Still other objects of the invention reside in the novel arrangements and combinations of parts as more fully hereinafter set forth.

In the drawings:

Figure 1 is a side elevation, partly in section, of the machine embodying my invention;

Figure 2 is a top plan view thereof;

Figure 3 is an end view thereof;

Figure 4 is a cross-section on the line 4—4 of Figure 1.

1 is the standard adapted to rest upon a suitable work-bench 2 and to be clamped thereto by the clamp 3. At its upper end 40 the standard is provided with the laterally-extending spaced arms 4 and 5, preferably in vertical alignment. The shaft 6 extends substantially axially through the lower arm 4 and is rotatably mounted in suitable bearings 7 at the ends of the arm. 8 is an annular cutting tool non-rotatably mounted upon the outer end of the shaft 6.

9 is a cooperating annular cutting tool non-rotatably mounted upon the outer ends 50 of the shaft 10, which extends approximately axially through the upper arm 5. This shaft is rotatably mounted at its inner end in the stationary bearing 11 of the upper arm. The shaft 6 is rotated by means of the crank 12 55 fixedly secured to its inner end. For rotating the shaft 10 the gear 13 is provided

between the crank 12 and the inner end of the lower arm 4 and meshing with the gear 14 non-rotatably secured upon the inner end of the shaft 10.

For the purpose of adjusting the cutting tools toward each other, the shaft 10 is mounted at its outer end in a movable bearing 15, which bearing is adjustable toward the shaft 6 by suitable means, such as the adjustment screw 16, there being sufficient clearance between the movable bearing 15 and the shaft 10 and the upper arm 5 to permit of movement of the bearing and shaft relative to the arm. By adjusting the bearing 15 toward the shaft 6 it is readily seen that the outer end of the shaft 10 and the cutting tool 9 are adjusted so that the cutting tool 9 will cooperate with the cutting tool 8 to cut off the tube 17, shown in dotted lines, which is telescopically mounted upon the outer end of the lower arm 4.

For the purpose of indicating the length of tube to be cut, the lower arm 4 is provided with a series of suitable gradations 18 80 extending longitudinally upon the side surface of the arm. For limiting the inward movement of the tube 17 over the lower arm 4, the adjustable stop 19 is provided which extends downward and adjacent to the lower arm 4 and is slidably mounted upon the shaft 20 which extends longitudinally of the upper arm 5 and is mounted at its opposite ends in suitable bearings 21 upon the upper arm. For securing this stop in its adjusted position, the set screw 22 is provided adapted to engage the shaft 20.

Another important feature of my invention is the provision of cooperating crimping tools 23 and 24 non-rotatably mounted upon the shafts 6 and 10 respectively and outside the cutting tools 8 and 9. These crimping tools are of smaller diameter than their corresponding cutting tools, the arrangement being such that after telescoping the tube upon the lower arm 4, the cutting tools 9 are adjusted toward each other sufficiently to cut the tube, there still being clearance between the crimping tools and the tube. The tube after being cut is moved outward and its end positioned between the crimping tools which are then adjusted sufficiently toward each other to crimp the end of the tube and thereby contract the same.

From the above description it will be readily seen that I have provided a simple construction of machine for cutting tubes,

such as stove-pipes, etc., to desired lengths without damaging either end portion of the tube. Furthermore, it is seen that the cutting tools are adjustable toward each other and are rotated by gears, the axes of which are relatively stationary. Another important point is that the machine is portable and can be readily secured in place. Also crimping tools can be combined with the cutting tools so that after the tube has been cut it can be immediately crimped.

What I claim as my invention is:

In a tube-cutting machine, the combination with a standard, of a pair of laterally extending spaced hollow arms mounted upon said standard, shafts journaled in suitable

bearings in said arms, one of said bearings being adjustable vertically, means for rotating said shafts simultaneously, cooperating annular cutting tools secured to said shafts adjacent to one end thereof, cooperating crimping tools secured to said shaft adjacent to said cutting tools, said crimping tools having a smaller diameter than said cutting tools, one of said arms bearing suitable indicia, a shaft extending longitudinally of the other of said arms, and an adjustable arcuate-shaped stop carried by the last mentioned shaft engaging the arm provided with said indicia.

In testimony whereof I affix my signature.

PAUL J. KOHLER.
